DESIGN FOR A SPECTACLE FRAME

Albert George McNeill, Philadelphia, Pa., assignor
to Bachmann Bros., Inc., Philadelphia, Pa., a
corporation of Pennsylvania

Application September 18, 1946, Serial No. 133,383

Term of patent 14 years

(Cl. D57—1)

To all whom it may concern:

Be it known that I, Albert George McNeill, a citizen of the United States, residing at Philadelphia, in the county of Philadelphia and Commonwealth of Pennsylvania, have invented a new, original, and ornamental Design for a Spectacle Frame, of which the following is a specification, reference being had to the accompanying drawing, forming a part thereof, in which

Figure 1 is a perspective view of the spectacle frame showing the new design.

Figure 2 is a view showing a front elevation of the spectacle frame.

Figure 3 is a section through the spectacle frame taken on line 3—3 of Figure 2.

Figure 4 is a section through the spectacle frame taken on line 4—4 of Figure 2.

The design comprises a spectacle frame with the outer surface of the frame rounded and with flanges at the edges extending backward to meet the surfaces of the face of a wearer of glasses.

I claim:

The ornamental design for a spectacle frame, as shown and described.

ALBERT GEORGE McNEILL.
